Primary Examiner — Joseph Kukella*Assistant Examiner* — Francis Wilder(74) *Attorney, Agent, or Firm* — Conley Rose, P.C.(57) **CLAIM**

The ornamental design for a computer, as shown.

DESCRIPTION

FIG. 1 is a front left perspective view of a computer in accordance with our new design;

FIG. 2 is a rear right perspective view thereof;

FIG. 3 is a top view thereof;

FIG. 4 is a bottom view thereof;

FIG. 5 is a left side view thereof;

FIG. 6 is a right side view thereof, for the side opposite that of FIG. 5;

FIG. 7 is a front view thereof; and,

FIG. 8 is a back view thereof.

The broken lines shown in the drawings are only provided to illustrate the environment of the design, and form no part of the claimed design.
